(57) **CLAIM**

The ornamental design for a fish-holding device for performing tests with fish, as shown and described.

DESCRIPTION

FIG. 1.1 is a front side view of a fish-holding device for performing tests with fish, in accordance with one embodiment or aspect of the present design;

FIG. 1.2 is a left side view of the fish-holding device for performing tests with fish shown in FIG. 1.1;

FIG. 1.3 is a top view of the fish-holding device for performing tests with fish shown in FIG. 1.1;

FIG. 1.4 is a bottom view of the fish-holding device for performing tests with fish shown in FIG. 1.1;

FIG. 1.5 is a side sectional view of the fish-holding device for performing tests with fish shown in FIG. 1.1 taken along line A-A as shown in FIG. 1.1;

FIG. 1.6 is a perspective view of the fish-holding device for performing tests with fish shown in FIG. 1.1; and,

FIG. 1.7 is the perspective view of the fish-holding device for performing tests with fish of FIG. 1.6 with additional exemplary environmental details.

Right and back side views of the fish-holding device for performing tests with fish are omitted because the right side view and back side view are identical to the left side view of FIG. 1.2 and the front side view of FIG. 1.1, respectively. The broken lines shown in FIGS. 1.1-1.7 depict the environment in which the fish-holding device for performing tests with fish is used and do not form part of the claimed design.
